UNITED STATES PATENT OFFICE.

ADOLF BAUMANN, OF BADEN, SWITZERLAND, ASSIGNOR TO AKTIENGESELLSCHAFT BROWN, BOVERI & CIE., OF BADEN, SWITZERLAND, A JOINT STOCK COMPANY.

CENTRIFUGAL COMPRESSOR OR BLOWER.

Application filed April 12, 1926, Serial No. 101,417, and in Germany April 23, 1925.

This invention relates to the construction of centrifugal compressors or blowers and has to do particularly with the construction of the impeller wheels.

5 The general object of the invention is the provision of a construction which will permit of operation of the machines at increased peripheral speeds without necessitating a proportionate increase in the weight and size 10 of the impeller wheels.

Another object is the provision of a construction which will afford increase of strength in the impeller wheels without necessitating increase in the weight.

15 A further object is the provision of a construction which will reduce the cost of manufacture through the utilization of standardized portions in the construction of wheels of different diameters.

20 Other and further objects will be pointed out or indicated hereinafter or obvious to one skilled in the art upon an understanding of the invention.

In the drawing forming a part of this 25 specification are illustrated certain constructions whereby the invention may be availed of, but it is to be understood that the various embodiments of the invention may differ in detail from the construction here shown 30 for purpose of illustration.

In the drawing,

Fig. 1 is a marginal view or side elevation of an impeller blade.

35 Fig. 2 is a perspective view of one form of blade section.

Fig. 3 is a transverse sectional view of another form of blade section.

40 Fig. 4 is a diagrammatic illustration of a group of impeller wheels, same shown in part diametrical section.

Fig. 5 is another group of such wheels illustrated in similar fashion, and

Fig. 6 is a similar illustration of a third group of wheels.

45 Limitations are imposed on the peripheral speed at which centrifugal blowers or compressors may be operated and upon the effective output, by the weight of the impeller wheels. When operated at high peripheral 50 speeds, the blades must be of very substantial strength, but substantial increase in the weight of metal in the blades in turn increases the stresses to which the shroud discs and hubs are subjected, thus necessitating a 55 commensurate increase in the weight of those

parts. As the weight of the impeller wheels is increased, however, the number that may be mounted on a single shaft is reduced, owing to consideration of critical speed. Various types of light metal of high tensile 60 strength, such as duraluminium are available, but heretofore the use of such metals for the blading has presented difficulties making it impracticable due to the differences in the thermal expansion coefficients between such metals and the steel discs which support the blading.

The present invention makes possible the use of such metals in the blading, with the resulting advantages in the direction of increased strength for weight and size in both blades and discs, the increase of operating speeds and output, together with various other advantages in the direction of economy of production. The nature of the invention will be understood by reference to the drawing in which Fig. 1 shows a marginal view or side elevation of an impeller blade, the same being made up of a plurality of small sections 10, one form of section being shown in detail in Fig. 2, and appropriately shaped end sections 11. These sections may be formed of a suitable light metal of high tensile strength such as duraluminium, by die-casting or otherwise, the 70 sections being provided, if desired, with the integrally formed attaching rivets 12 on their margins. For purpose of weight reduction they may be formed with interior cored spaces 14. The sections are assembled 75 between the shroud discs 15 and 16 and secured thereto by means of the rivets 12, the several sections being disposed in proper relationship to constitute a blade of the desired form.

80 The several sections forming a blade are not placed in close abutment, but small spaces 17 are left between the adjacent edges. These constitute expansion spaces accommodating the expansion of the portions of the sections beyond the rivets, thus relieving 85 both the discs and the blades of the effects of a cumulative expansion of metal throughout the length of the blade. Not only does this relieve the rivets of the shearing action 90 which would result from the difference in expansion of the steel discs and alloy blades, but also contributes to the strength and 95 stability of the connection of the two discs through the medium of the blades.

By suitable selection of sizes for the blade sections, uniform standardized sizes may be employed in the construction of impeller wheels of different diameters. For example, 5 Fig. 4 shows a series of impeller wheels graded into different sizes so as to operate in accordance with a definite law governing the design of such elements, the different sizes varying both in diameter of the wheel 10 and in width of the blades.

Fig. 5 shows another group in which the diameters correspond respectively to the diameters of the forms B, C and D of Fig. 4, but the blades in each are narrower than 15 those in the wheels of corresponding diameter in the other group.

In Fig. 6 are shown sections of two other wheels, that designated H corresponding in diameter to wheels F and C, and that designated 20 I corresponding in diameter to G and D, but in each instance the blades are of less width. However, the width of the blades in the forms H, E and A are the same, and the sections of which the blades are formed 25 are the same size. The same holds true for the forms I, F and B and for the forms G and C. This demonstrates how wheels of different sizes may be built up using blade sections of uniform design and size.

30 A further advantage accrues from the construction of the blades in this fashion by virtue of the facility by which advantageous details of construction may be incorporated for example, in Fig. 3 is shown a blade section in which the member is given a form 35 constituting a beam of uniform strength throughout its width.

What I claim is:—

1. Construction for rotary compressors

comprising shroud discs and interposed impeller blades, the respective blades being formed of a plurality of sections of a light metal different from that of the discs, with expansion spaces between sections. 40

2. In a rotary compressor, an impeller 45 wheel comprising shroud discs and intervening blades secured to the discs, respective blades being formed of a plurality of separate sections secured individually to the discs with expansion spaces between sections. 50

3. In a rotary blower, an impeller wheel comprising shroud discs and intervening impeller blades, respective blades being formed of a plurality of sections having integral fastening members seated in the discs, the 55 sections arranged with intervening expansion spaces.

4. In an impeller wheel, an impeller blade comprising a plurality of sections arranged with intervening expansion spaces, the sections having marginal securing members. 60

5. An impeller wheel comprising shroud discs and intervening impeller blades, the blades comprising a plurality of identical sections of light metal different from that 65 of the discs, the sections constituting a blade being arranged with intervening expansion spaces.

6. A blade construction for impeller wheels comprising identical blade sections 70 formed of light metal and having marginal mounting members, said sections having smooth external faces and internal cavities for lightening effect.

In testimony whereof I have hereunto subscribed my name at Zurich, Switzerland, on the 26 day of March A. D. 1926. 75

ADOLF BAUMANN.
